7 Claims. (Cl. 315—84.6)

This invention relates to counting devices, and more particularly to those using numeral-indicating discharge tubes which give luminous indication of numbers.

The primary object of the present invention is to provide a counting device for counting the number of incoming electrical pulses and visibly indicate the same by glow discharges of numeral-shaped cold cathodes of a discharge tube, in which none of the numeral-indicating cathodes is luminant during the time interval from the instant of its resetting to the arrival of the first electrical pulse, thereby obtaining a clear indication of the number.

There are other objects and particularities of the present invention, which will be made obvious from the following detailed description of the invention with reference to the accompanying drawings, in which:

FIG. 1 is a schematic diagram showing a typical embodiment of the invention; and

FIGS. 2, 3 and 4 show three modifications of the embodiment shown in FIG. 1, respectively.

In conventional counting devices using numeral-indicating discharge tubes, in general, during the time interval from the instant of resetting of the discharge tube to the arrival of the first electrical pulse for next numeral indication, the discharge tube is in operation to indicate "0," waiting for the arrival of the above-mentioned first pulse. Consequently, during the above-mentioned time interval, all the numeral-indicating cathodes except "0"-indicating one are subject to contamination by vaporized substances from the "0"-indicating luminant cold cathode, and when they become luminant by arrival of respective pulses, it is difficult to obtain a clear luminant indication of the respective digits. Such a defect is especially detrimental in counting devices for dealing with multi-digit numbers.

The present invention primarily contemplates the elimination of the above-mentioned defect, and will be described in detail, taking embodiments for ternary-number indication as an example, but it will be obvious that the invention is applicable also to binary, decimal, and other number indication.

It should also be noted that, although triodes are employed as the elements serving for amplification or switching in the illustrated embodiments, other multi-electrode tubes, transistors, and equivalents may also be used therefore.

Referring to FIG. 1, the counting device comprises triodes V_0 , V_1 , V_2 , and V_3 , with their cathodes connected to ground. Their grids are connected to a common input terminal P through condensers C_{0g} , C_{1g} , C_{2g} , and C_{3g} , respectively, and also to a common negative bias source $-V_{b2}$ through resistors R_{0g} , R_{1g} , R_{2g} , and R_{3g} , respectively. With respect to the triode V_0 only, there is provided a reset switch S connected between resistor R_{0g} and negative bias source $-V_{b2}$. The anode of the triodes are connected to a common positive electrical source $+V_{b1}$ through load resistors R_{0p} , R_{1p} , R_{2p} , and R_{3p} , respectively. The anode of triode V_0 is also connected to the grids of triodes V_1 , V_2 , and V_3 , through resistors R_{01} , R_{02} , and R_{03} , respectively, and the resistor R_{02} only is parallel-connected with a condenser C_{02} . The anode of triode V_2 is also connected to the grids of triodes V_0 , V_1 , and V_3 , through resistors R_{20} , R_{21} , and R_{23} , respectively, and the resistor R_{23} only is shunted by a condenser C_{23} .

2

Similarly, the anode of triode V_3 is connected to the grids of triodes V_0 , V_1 , and V_2 , through resistors R_{30} , R_{31} , and R_{32} , respectively, and the resistor R_{31} is shunted by a condenser C_{31} , while the anode of triode V_1 is connected to the grids of triodes V_0 , V_2 , and V_3 , through resistors R_{10} , R_{12} , and R_{13} , respectively, and the resistor R_{12} is shunted by a condenser C_{12} .

The anodes of triodes V_1 , V_2 , and V_3 are connected to cold cathodes T_{k0} , T_{k1} , and T_{k2} , respectively, of a numeral-indicating discharge tube T , through a matrix circuit M . The discharge tube T is provided with a common anode electrode T_p which is connected to a positive electrical source $+V_{b3}$ through a resistor R .

The counting device is resetted by operating the reset switch S in the order of close-open-close, whereupon triode V_0 only is rendered conductive, while remaining three triodes V_1 , V_2 and V_3 are rendered non-conductive, thus ready for reception of incoming pulses. At this instant, the discharge tube T is not yet in operation.

When the first of successive negative trigger pulses has arrived at the input terminal P , negative potentials are applied to the grids of triodes V_0 , V_1 , V_2 and V_3 through condensers C_{0g} , C_{1g} , C_{2g} and C_{3g} , respectively, whereupon triode V_0 is rendered non-conductive, and its anode potential rises abruptly, resulting in rises of grid potentials of triodes V_1 , V_2 , and V_3 through resistors R_{01} , R_{02} and R_{03} , respectively. In this case, however, triode V_2 only has its grid resistance R_{02} shunted by condenser C_{02} , so that the triode V_2 is rendered conductive prior to the remaining triodes which remain non-conductive. When triode V_2 becomes conductive, its anode potential drops and acts through the matrix circuit M to lower the potential of cold cathode T_{k1} of discharge tube T . Whereupon, the tube T operates to give luminous indication of digit "1."

When the second negative trigger pulse has arrived at the input terminal P , similar operation takes place to transfer the conduction of triode V_2 to conduction of triode V_3 , because the anode of V_2 and the grid of V_3 are connected with the condenser C_{23} in parallel with the resistor R_{23} , and the numeral-indicating discharge tube T changes its visible indication from "1" to "2." Similarly, upon arrival of the third pulse, the conduction is transferred from triode V_3 to triode V_1 , because the anode of V_3 and the grid of V_1 are connected with the condenser C_{31} in parallel with the resistor R_{31} , and the numeral-indicating discharge tube T gives luminous indication of "0" for the first time. From the fourth pulse, the conduction circulates from V_1 to V_2 and then to V_3 and returns to V_1 and the same operation repeats, and only when the reset switch S is operated in the order of close-open-close does the triode V_0 conduct.

On the other hand, the drop in the anode potential of triode V_1 sends a new negative pulse to another counting device, not shown, provided for digits one place higher, and the latter begins to operate for the first time.

According to the present invention, during the time interval from the instant of resetting to arrival of the first pulse, the numeral-indicating discharge tube T does not give luminous indication of "0," so that it might be difficult to confirm whether or not the counting device is operating in the satisfactory manner. In case when such a confirmation is required, a neon lamp L and its protective resistor r in series therewith may be provided as shown by dotted line in FIG. 1, and the proper operation of the counting device can be confirmed by the light of neon lamp L .

In the modification shown in FIG. 2, the reset switch S is disposed between the cathodes of triodes V_1 , V_2 and V_3 , and the ground, and the grid of triode V_0 is connected to the negative bias source $-V_{b2}$ through the resistor R_{0g} . Otherwise, the arrangement is same as in FIG. 1. In this case also, the switch S may be operated in the order of

close-open-close for resetting the device, to render triodes V_1 , V_2 and V_3 non-conductive and triode V_0 only conductive, as in the case of FIG. 1.

In the modification shown in FIG. 3, a relay coil R_e is connected in the anode circuit of triode V_0 , with its contact point S' inserted in the anode circuit of numeral-indicating discharge tube T . In this case, during the time interval from the resetting to arrival of the first incoming pulse, during which the triode V_0 is reversed from conductive to non-conductive, the relay contact point S' is held open by the anode current of triode V_0 , whereby the discharge tube T is further assured to be inoperative.

In the modification shown in FIG. 4, the relay coil R_e is connected between the load resistors R_{1p} , R_{2p} and R_{3p} , and the positive electrical source $+V_{b1}$, and shunted by a condenser. Its contact point S' is inserted in the anode circuit of numeral-indicating discharge tube T as in FIG. 3. In this case, during the time interval when the triode V_0 is non-conductive, any of the remaining triodes V_1 , V_2 and V_3 being conductive, the operating current of the conductive triode holds the contact point S' closed for obtaining the result same as in FIG. 3.

As will be understood from the about description, according to the present invention, the conventional ring counter comprising required number of triodes or equivalent elements for amplification or switching, in order to control the respective cold cathode potential relative to the anode of the numeral-indicating discharge tube, is additionally provided with another circuit of amplifying or switching element, whereby the numeral-indicating discharge tube is held inoperative during the time interval from the instant of resetting to arrival of the first incoming pulse. Consequently, the cold cathodes other than that for "0" indication are never contaminated by vaporized substances from the "0"-indicating cold cathode which is always luminant in the conventional device. In addition, consumption of electrical power is saved, wrong indication is eliminated, and the useful life of the device is prolonged.

In practice, a plurality of counting devices embodying the present invention are required corresponding to the number of places of the number to be counted and indicated, but it is preferred to employ a conventional counting device for the lowest place and those according to the present invention for the higher places.

What is claimed is:

1. A counting device comprising a ring counter having a plurality of sequentially arranged counting elements for counting the number of incoming pulses, each of said counting elements having a control electrode and two output electrodes, a numeral indicating discharge tube having a plate and a plurality of numeral shaped cold cathodes opposed to the plate, matrix circuit means operatively connecting one of said output electrodes of each said

counting element to respective cathodes of said discharge tube, the other output electrode of each said counting element being connected to a common ground, a bias voltage and an incoming pulse receiving terminal each connected to the control electrode of each said counting element, first means connecting an output electrode of the first counting element to the control electrodes of each subsequent counting element, a condenser interconnecting the control electrode of a third counting element with said first counting element output, second means including a condenser connecting an output electrode of a last counting element to the control electrode of a second counting element, said first and second means forming circuit means for rendering said discharge tube inoperative only during the time interval from the instant of resetting of the device to the arrival of the first of successive incoming pulses.

2. A counting device according to claim 1 wherein said elements are triode vacuum tubes.

3. The counting device according to claim 1 wherein said elements are transistors.

4. A counting device according to claim 1 wherein a reset switch is provided in said first-stage element.

5. A counting device according to claim 1 wherein a neon lamp is provided in the output terminal of said first element for indicating conduction of said first stage element.

6. A counting device according to claim 1 wherein a relay is provided in a circuit applying power to said first-stage element to control the plate circuit of said discharge tube by said relay.

7. A counting device according to claim 1 wherein a relay is provided in a circuit supplying power to the elements from the second stage onwards to control the plate circuit of said discharge tube with the relay.
